UNITED STATES PATENT OFFICE.

STEPHEN P. WALLING, OF SOUTH EDMESTON, NEW YORK.

GRINDING-MILL.

SPECIFICATION forming part of Letters Patent No. 372,726, dated November 8, 1887.

Application filed December 10, 1886. Serial No. 221,201. (No model.)

To all whom it may concern:

Be it known that I, STEPHEN P. WALLING, of South Edmeston, in the county of Otsego and State of New York, have invented certain 5 new and useful Improvements in Grinding-Mills, of which the following is a specification.

My invention relates to that class of grinding-mills in which two horizontal disks or grinding-surfaces are employed, and has reference more particularly to a novel construction of devices, as hereinafter fully set forth and claimed, whereby the upper stone or disk is permitted to adapt or adjust itself to the running-stone.

15 In the drawings, Figure 1 is a vertical central section through a mill, showing my improvements applied thereto; Figs. 2 and 3, perspective views of the details; Figs. 4 and 5, vertical sectional views at right angles to each 20 other, and Fig. 6 a top plan view on the line zz of Fig. 5.

The present invention consists in a novel construction and arrangement of devices which are secured to the mill-casing and the 25 upper stone, and which permit the stone to rock or tip vertically upon horizontal journals in any direction at right angles to each other.

The invention further embraces a novel device for securing the aforesaid mechanism to the upper stone.

A indicates the mill-casing, B the upper stone or disk, C the running-stone or disk, and D the mill-spindle, all of which parts may 35 be of any usual construction, except as hereinafter pointed out.

The form of mill shown in the drawings is the same as that represented in Letters Patent No. 252,158, issued to me January 10, 40 1882, though it is obvious that various features therein shown, and also herein shown, merely for the purpose of illustration, may be varied without departing from the spirit of the present invention.

45 The cap or cover E of the mill casing is provided with a central hole, within which is fitted a hub or collar, F, as shown in Figs. 1, 2, 3, 4, and 5, which collar is open from end to end. It is provided with a lateral circumferential flange, a, near its upper end, which 50 bears against the under face of the cap or

cover E, and is further provided with a depending flange or rim, b. Depending from the under face of the flange a are two lugs, c c, diametrically opposite to each other, as shown in 55 Figs. 3 and 4, and separated a distance from the depending flange b. The lugs c extend downward, so that their lower edges shall be on line with the lower edge of the flange b, and each of the lugs, together with the flange, is 60 provided with a seat or bearing, d, as shown in Figs. 3 and 4.

G represents a collar which in most particulars resembles the collar F, being provided with lugs c' and an upright flange, b', which 65 are in all respects similar to and correspond with the lugs c and flange b of collar F. It will be noticed, however, that the lugs c' are at right angles to the lugs c c of collar F, and the bearings d' in the lugs c' and flange b' are 70 at right angles to those of collar F, as shown in Fig. 3. The upper edge of flange b' and the lower edge of flange b are curved, as shown in Figs. 3, 4, and 5, so as to permit one collar to rock upon the other.

75 G² indicates a collar threaded externally to screw into the collar G, the collar G² being provided with laterally-extending lugs a², which are set into the lower face of the stone, and thereby prevent the collar from becoming 80 loose and turning independently of the stone or disk B.

H indicates a ring which surrounds or encircles the flanges b b', the ring extending between the flanges b b' and the lugs c c', as shown 85 in Figs. 3, 4, 5, and 6. This ring H is provided with two sets of journal or pins, e and e', in the same horizontal plane, the two pins or journals of each set being diametrically opposite to each other, while the two sets of journals 90 are at right angles to each other, as shown in Figs. 3 and 6.

The pins e c c' e' project on both sides of the ring H, and two of them, e c, are seated at their inner ends upon the upper edge of flange 95 b' of collar G, while their outer ends are seated in the upper faces of the lugs c c', as shown in Figs. 2, 3, 5, and 6. The other set of pins, e' e', are seated at their inner and outer ends, respectively, in the flange b and lugs c c, as shown 100 in Figs. 2, 3, and 4.

The pins e e' are secured rigidly to the ring

H and prevented from turning therein, thus permitting the collars F and G to swing or oscillate upon the pins or journals, the two collars swinging at right angles to each other, 5 one upon the pins $e e'$ and the other upon the pins $e' e'$, and it will be seen that the upper stone may thus adapt or adjust itself to the lower stone or disk.

Caps or plates f will be secured to the lugs $c c'$, in order that the pins $e e'$ may be held to their seats, and in order to regulate the freedom with which the collars F and G may turn upon the pins $e e'$, and for the further purpose of taking up wear these caps will be made adjustable by means of set-screws g , as clearly shown in Figs. 2, 5, and 6. The caps or plates f will, by preference, be made somewhat elastic.

By making the flanges $b b'$ of the form shown and placing them one above the other they 20 may be brought close together and yet tip or rock freely upon each other. It will be noticed that a clear and unobstructed passage is left for the feed of the material, and that the escape of material between the collars F G is 25 prevented by the ring H.

Having thus described my invention, what I claim is—

1. In combination with casing A, cap E, and disks B C, a collar, F, secured to cap E and 30 provided with a depending flange, b , a collar, G, secured to disk B and provided with an upright flange, b' , and a ring, H, encircling the flanges $b b'$ and provided with two series of journals e , and e' , which latter are pivotally 35 connected, respectively, with the collars G and F, all substantially as shown.

2. In combination with casing A, cap E, and

disks B C, a collar, F, secured to cap E and provided with a depending flange, b , curved on its lower edge, substantially as shown, a 40 collar, G, secured to disk B and provided with an upright flange, b' , curved to correspond to flange b , a ring, H, encircling the flanges $b b'$, and pins $e e'$, pivotally connecting the flanges with the ring.

3. In combination with casing A, cap E, and disk B, collar F, provided with depending flange b and lugs $c c'$, sockets or bearings d in the flange and lugs, collar G, provided with upright flange b' , lugs $c' c'$, and bearings d' , ring H, encircling the flanges $b b'$ and provided with journals $e e' e' e'$, and plates f , applied to the journals, all substantially as shown.

4. In a grinding-mill, the combination, with casing A, cap E, and disk B, of collars F G, 55 secured, respectively, to the cap and disk, a ring, H, provided with two sets of pins, $e e'$, seated in the collars G and F, respectively, and adjustable plates or caps, as f , applied to the pins $e e'$, all substantially as shown.

5. In a grinding-mill, and in combination with the fixed stone B, having an eye, a collar, G, resting upon the upper face of the stone and threaded internally, and a collar, G^2 , fitting within the eye, screwing into collar G, 65 and provided with lugs a^2 , which are set into the lower face of the stone, all substantially as shown.

In witness whereof I hereunto set my hand in the presence of two witnesses.

STEPHEN P. WALLING.
